UNITED STATES PATENT OFFICE.

JAMES ALLINGHAM, OF CHICAGO, ILLINOIS.

DESIGN FOR A SUPPORTING-LEG.

No. 39,550.

Specification for Design.

Patented Sept. 15, 1908.

Application filed July 13, 1908. Serial No. 443,382. Term of patent 3½ years.

To all whom it may concern:

Be it known that I, JAMES ALLINGHAM, a citizen of the United States, residing at Chicago, in the county of Cook and State of Illinois, have invented a new, original, and ornamental Design for Supporting-Legs, of which the following is a specification, reference being had to the accompanying drawing, forming a part hereof.

The figure is a view in side elevation of a supporting leg, showing my new design.

I claim—

The ornamental design for a supporting leg, as shown.

JAMES ALLINGHAM.
